GRINDING MACHINE

Erwin G. Roehm, Norwood, Ohio, assignor to
 Cincinnati Grinders Incorporated, Cincinnati,
 Ohio, a corporation of Ohio

Application November 22, 1933, Serial No. 699,203

17 Claims. (Cl. 51—103)

This invention relates to improvements in machine tools and particularly to improvements in grinding machines.

One of the principal objects of the present invention is the provision of a new and improved spindle oscillating mechanism as employed with grinding machines.

Another object of the invention is the provision of a spindle reciprocating mechanism of the hydraulically actuated type in which the stroke of the reciprocator may be varied and accurately maintained.

A further object of the invention is the provision of a spindle reciprocating mechanism in which the rate of travel of the reciprocator may be varied; in which the rate of reciprocation of the spindle may be varied in each direction and in which the reciprocation may take place at a variable slow rate in one direction and a rapid rate in the reverse direction.

A further object of the invention is the provision of an improved spindle reciprocating mechanism in which the spindle may be reversed without forcibly engaging a positive stop, thereby preventing jars and vibrations to the machine; in which a dwell is provided at each end of the reciprocatory stroke, and in which the said dwell may be varied in duration before effecting its reverse reciprocation.

A still further object of the invention is the provision of a spindle reciprocating mechanism which is adapted to be universally adjustable for thereby controlling all of the functions performed by a spindle reciprocating mechanism.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

In the drawings:

Figure 1 is a front elevational view of a grinding machine embodying the improvements of this invention.

Figure 2 is a top plan view of the machine shown in Figure 1.

Figure 3 is a longitudinal fragmentary sectional view through the grinding wheel spindle taken substantially on line 3—3 of Figure 1.

Figure 4 is a fragmentary sectional view taken on the same line as Figure 3, but continuing from where Figure 3 stops and particularly illustrating the reciprocating mechanism.

Figure 5 is a sectional view taken on line 5—5 of Figure 4.

Figure 6 is a sectional view taken on line 6—6 of Figure 4.

Figure 7 is a fragmentary sectional view taken on line 7—7 of Figure 4.

Figure 8 is a sectional view taken on line 8—8 of Figure 5.

Figure 9 is a sectional view taken on line 9—9 of Figure 5.

Figure 10 is a view taken substantially on line 10—10 of Figure 1.

Figure 11 is a view partly in section and partly in elevation taken on line 11—11 of Figure 10.

Figure 12 is a sectional view taken on line 12—12 of Figure 10.

Figure 13 is a diagrammatic view showing the hydraulic circuits involved in the invention.

Throughout the several views of the drawings similar reference characters are employed to denote the same or similar pieces.

As was noted above, this invention pertains primarily to improved means for effecting the axial reciprocation of a spindle and the like, particularly grinding wheel spindles, whereby a relative motion is had between the wheel and work to break up grinding lines on the work. The invention is illustrated in the drawings as employed with a centerless grinder, but it is to be understood that it is not limited to this type of machine, but has application with center type grinders, as well as other types of machine tools in which it is desired to have relative tool and work movements.

The grinding machine shown in the drawings comprises a bed 15 having rising thereabove at one end thereof a pedestal bearing housing 16 in which is journaled a spindle 17. The bed 15 is further provided on its upper surface with a guide 18 which extends from the grinding wheel bearing to the end of the bed. The guide 18 is received in a corresponding guideway formed in the under surface of the slide 19, in turn providing a guide 20 on its upper surface for a second or upper slide 21. The upper slide 21 has secured thereto a head 22 in which is journaled a spindle 23 for a regulating wheel 24. The regulating wheel 24 is opposed to a grinding wheel 25 secured in any desirable manner to the spindle 17 and the said wheels are spaced from one another to provide a grinding throat 26 in which is located the work 27.

The wheel head 22 of the regulating wheel supports on the upper surface thereof a trueing mechanism 28 whereby the face of the wheel 24 is maintained in a true accurate condition for proper engagement with the work. The grinding wheel 25 is enclosed within a hood or guide 29 which confines the coolant usual with grinding machines and also provides a support 30 for a

trueing mechanism 31. The trueing mechanism 31 is adapted to be actuated relative to the wheel 25 for maintaining the face thereof in a true and sharp condition. In practice the grinding wheel 25 is rotated at a high rate of speed in a clockwise direction, while the regulating wheel 24 is rotated at a relatively slow, work controlling rate of speed also in a clockwise direction. By this construction the proximate portions of the said wheels which form the grinding throat 26 travel in an opposite direction.

The work is supported in the grinding throat by a work rest blade 32 which peripherally engages the work during the grinding operation. The blade 32 is mounted in a block 33 secured, in any desirable manner, to the inner end of the primary or lower slide 19.

In order to vary the width of the grinding throat 26 the slides 19 and 21 are adapted to be shifted relative to one another and to the bed 15. For this purpose the upper slide 21 has secured therein a nut 34 in threaded engagement with an adjusting screw 35 journaled in a housing 36 for rotative and axial movement relative thereto. The screw 35 projects beyond the housing 36 to receive a pilot or hand wheel 37 whereby the said screw 35 is rotated; its axial movement being obtained by means to be subsequently described and enclosed within housing 36. In order to move the slide 19 it is clamped to the upper slide 21 by means of the clamp 38, while to effect the independent movement of the slide 21 relative to the slide 19 the clamp 38 is opened to free the slides from one another and a clamp 39 is fastened to secure the lower slide 19 to the bed 15. In practice and to effect a relative feed between the work and grinding wheel the slides 19 and 21 are moved as a unit through the mechanism within the housing 36.

The mechanism within the housing 36 is illustrated in detail in Figures 10, 11 and 12, and as there shown comprises a slide block 40 secured to the screw 35 in such a manner that the screw has rotative movement relative thereto, but is axially shiftable therewith. The block 40 is mounted in a bearing 41 provided by the housing 36 and the said block has pivotally connected to opposite sides thereof one end of links 42 having their other ends pivotally secured to an arm 43 projecting from a bell crank lever 44. The lever 44 is pivotally connected at 45 and 46 to a web 48 and one wall of the housing 44. The second arm 49 of the bell crank carries a roller 50 adjustable relative thereto, which roller 50 is received in a cam slot 51 formed in one face of a cam plate 52. The cam slot 51 is provided with a portion 53 for rapidly shifting the slides and work toward the grinding wheel, which portion is followed by a portion 54 for gradually feeding the work into the grinding wheel to effect a stock removal from the work at the desired rate. The portion 54 terminates in a concentric portion 55 and effects a dwell in the feed of the work and wheel and permits a sparking out between the wheel and work whereupon cam portion 56 rapidly retracts the work from the grinding wheel. This portion 56 of the cam is followed by a second concentric portion 57 which holds the slides in a retracted position to permit a replacement of the work.

In order to rotate the cam 52 it is secured in any desirable manner to a cam shaft 58 rotatably journaled in a bearing 59 extending from

the web 48 or a wall of the housing 36. The shaft 58 projects beyond the bearing 59 to receive a worm wheel 60 in mesh with a worm 61 integral with or secured to a worm shaft 62. The worm shaft 62 projects beyond the housing 36 and has secured to said projecting portion a pulley, gear or the like about which is trained a flexible transmission member, such as a chain or belt 63 extending in turn about a small pulley or pinion 64 secured to the shaft 10 65 of a motor or prime mover 66 carried by the undersurface of the housing 36.

From the foregoing it will now be seen that the wheels 24 and 25 may be adjusted relative to one another to provide a grinding throat and that the work is automatically fed toward and from the grinding wheel. It is desired during the said grinding operation to effect the axial reciprocation of the grinding wheel and work. It is also desired to initiate the operation of this spindle and wheel reciprocating mechanism at the commencement of the grinding operation and to stop the said reciprocation upon retraction of the work from the wheel, which operation is effected by the means now to be described.

The cam shaft 58 is projected beyond the rear wall of the housing 36 and has keyed or otherwise secured to said projection 66 a second cam 67 having formed in one face thereof a cam track 68 shown in elevation and, therefore, most clearly in Figure 12. The cam track 68 is provided with two concentric portions 69 and 70 connected at opposite ends by cam portions 35 71 and 72. The cam track 68 is adapted to actuate a valve shifter arm which when in the position indicated by the portion 69 has the valve in one position and when in the position indicated by the portion 70 will be in a second 40 position. These positions of the valve represent respectively the operation of the spindle reciprocator and the stopping thereof, and the cam track 68 bears a definite relation to the cam track 51. Therefore, the spindle reciprocator 45 will be set in motion at the time the work first contacts with the grinding wheel and will be stopped upon retraction of the work from the grinding wheel.

The mechanism operable by the cam track 68 50 includes an arm 73 pivotally connected at 74 to a lug 75 secured in any desirable manner to the rear of the housing or casing 36. Intermediate its ends the arm 73 carries a roller 76 disposed within the cam track 68 and at its 55 upper end the arm 73 has a pin and slot connection 77 with the stem 78 of a valve 79. The valve 79 is of the sliding type and has formed thereon a pair of piston portions 80 and 81 forming between them a cannelure 82. The 60 cannelure 82 is adapted in one position of adjustment to connect ports 83 and 84, and in the second position of adjustment to connect ports 83 and 85.

The ports 83, 84 and 85 are plural in number 65 and extend radially through a valve bushing 86 which encloses the valve 79. The valve bushing 86 is pressed into a valve casing 87 secured in any desirable manner to the rear wall of the housing 36. The valve casing 86, 70 arm 73 and cam 67 are all enclosed within a suitable guard 88 secured to the rear wall of the housing 36. The valve 79 is shown in its operative position in Figure 12, where the spindle reciprocator is operating to effect axial recipro- 75

cation of the spindle and grinding wheel toward the left as there viewed.

The hydraulic circuit for effecting the operation of the spindle reciprocator will best be understood from the circuit diagram in Figure 13, which will be described in detail later.

The grinding wheel spindle is shown structurally in Figure 3, and as there shown, the pedestal bearing housing 16 carries bearings 89 and 90 in which the spindle is journaled for rotative movement. The forward end of the spindle 17 is provided with a tapered nose 91 on which is pressed and keyed a grinding wheel collet 92 providing the seat for the grinding wheel 25. A clamping plate 93 is secured to the collet 92 for clamping the wheel between itself and the wheel seat formed on the collet 92. Intermediate the bearings 89 and 90 the spindle 17 has keyed or otherwise secured thereto a pulley or sheave 94 shown in the drawings as a sheave of the multiple V type about which is trained the multiple V belts 95. It is understood that the V belts 95 are in turn trained about a suitable driving source from which the spindle derives its rotative power.

The spindle 17 at its rear end has projecting therefrom a hollow boss 96 receiving a bushing 97 which is provided on opposite sides with a keyway 98. Extending through suitable bores in the boss 96 are keys 99 which enter the keyways in the bushing 97. A collar 100 is clamped against the face of the boss 96 by means of a nut 101. For holding the bushing 97 within the bore in the boss 96 the bushing 97 is internally threaded and screwed on the inner end of a rod 102 which terminates within the boss 96. Also disposed within the boss 96 is a spring 103 abutting on one end with the bushing 97 and on the other end with the base of the bore of the boss and exerts its force against the bushing 97 to take up all backlash and the like between the threads of the said bushing and the rod 102.

The rod 102, see Figure 4, at its other end terminates in a wrench head 104 and collar 105. Seated against the end of the collar 105 is a ring 106 having projecting therefrom a key or keys 107 disposed within a correspondingly shaped keyway formed in the end of a hollow shaft or sleeve 108. The hollow shaft or sleeve 108 encircles the rod 102 and is clamped between the collar 105 and the ring 106 wherefore it is substantially integral with the spindle 17 to partake of all movement imparted to the spring. The rod 102 and sleeve 108 form the connection between the spindle reciprocator and the spindle itself whereby the movement of the reciprocator is imparted to the spindle.

As shown in Figure 4 the hollow shaft or sleeve 108 has secured to it intermediate its ends, as by the nut 109, the inner race 110 of a double anti-friction thrust bearing. The outer race 111 of this bearing is secured to the interior of an hydraulically actuated piston formed of two parts 112 and 113, the latter part forming the piston proper and carrying the piston rings. The piston 112-113 is adapted to be reciprocated by hydraulic pressure through a cylinder 114 which is closed at one end by a head 115 including a suitable stuffing box and packing. The other end of the cylinder 114 is likewise closed by a cylinder head 116 which also includes a packing or stuffing box. The cylinder 114 is secured through a radial flange 117 to a bracket member 118, in turn secured to a cylin-

drical flange or extension 119 of the pedestal bearing 16. From this it will be seen that the spindle reciprocating mechanism is completely enclosed within a housing secured to the pedestal bearing 16 at the end of the spindle.

The hydraulic mechanism for effecting the operation of the piston 112-113 is shown most clearly in Figure 13 to which reference is now had. As shown therein, there is provided a sump or tank 120 containing the hydraulic medium, preferably oil, which is to be circulated through the system for effecting the operation of the piston. Disposed above the tank 120 is a pump 121 and extending from one side thereof is the suction conduit or pipe 122 which terminates in the tank 120. Extending from the other side of the pump is a pressure pipe or conduit 123 terminating in a piston reverse valve indicated generally by the numeral 124. The valve 124 is adapted to be actuated by pressure directed to opposite ends thereof by a pilot valve indicated generally by the numeral 125 in Figure 13. The pilot valve 125 in turn is reversed or reversely operated by pressure under the control of a reversing valve adapted to be positively actuated and indicated in general by the numeral 126, as seen in Figure 13. These valves 124, 125, and 126 are structurally illustrated in Figures 5, 8 and 9, and as there shown, comprise a single valve block 127 secured in any desirable manner to the bracket 118 above the spindle bearing housing 16. The positively actuated valve 126, as shown in Figure 8, comprises a valve bushing 128 pressed into a bore 129 formed in the valve block 127. The bushing 128 is provided with a plurality of sets of radial ports 130, 131, 132, 133, 134, 135 and 136, each set of which is encircled by a similar groove 137 formed circumferentially of the bushing 128. Disposed within the bore and movable relative thereto is a spool type valve 138 having piston portions 139, 140 and 141, forming between them cannelures 142 and 143 which connect in different combinations the several sets of radial ports.

Integral with the valve 138 is a stem 144 having formed in outer end, see Figure 4, a notch 145 receiving the ball end 146 of a valve shifter finger 147. The finger 147 is pinned or otherwise secured to a shaft 148 mounted for rocking or oscillating movement in bearings provided by the cylinder head 116. The shaft 148 crosses a notch or way 149 formed in the said cylinder head 116 at which point the shaft has secured thereto an arm 150, the free end 151 of which is mounted in a space 152 provided between a flange 153 and a nut 154. The flange 153 is integral with a sleeve nut 155 on which the nut 154 is threaded; the sleeve nut 155 being in turn threaded on the extension sleeve 156 integral with and extending from the piston 113. From this it will be seen that the space 152 may be varied for varying the stroke of the piston since as the flange 153 and nut 154 are relatively moved the time between shifting the valve 138 will be varied, thereby permitting a different length of piston stroke between valve reversals.

The ports 130 and 136 of the valve bushing 128 are drain ports for draining any leakage past the ends of the valve and are respectively connected, see Figure 13, with drain conduits 157 and 158 which empty into a conduit 159 that terminates in the sump or tank 120. The ports 75

133 have connected with them one end of a pressure conduit 160 which at its other end connects with the pressure conduit 123. The ports 132 connect with one end of a pipe or conduit 161 which terminates at one end of the valve 125 while the ports 134 connect with one end of a port or conduit 162 that terminates at the other end of the said pilot valve 125. The ports 131 and 135 respectively connect with 10 branch discharge conduits 163 and 164 emptying into conduits 165, 166 and 167, the latter of which terminates in the sump or tank 20.

As was above noted, the pilot valve 125 is adapted to be pressure actuated for which purpose the conduits 161 and 162 are provided for conveying the pressure from the conduit 160 to the opposite ends thereof. This valve 125 is shown most clearly in Figure 9 and comprises a valve bushing 168 which is pressed into a bore 20 169 in the valve block 127. The bushing 168 is provided with a plurality of sets of radial ports 170, 171, 172, 173, 174, 175 and 176, each set of ports being encircled by a similar circumferential groove 177 formed in the exterior of the 25 bushing 168. Disposed within the bore in the valve bushing 168 is a valve 178 adapted to be shuttled relative thereto between adjustable stops 179 and 180. The stops 179 and 180 are identical in construction and each includes a 30 threaded stem 181 threaded into a bonnet 182 in turn threaded in the ends of the bore 169 in the valve block 127.

The shuttle valve 178 is of the spool type having formed near opposite ends thereof piston 35 portions 183 and 184, from opposite sides of which project slightly reduced portions 185 and 186. The portions 185 and 186 respectively co-operate with ports 171 and 175 to provide hydraulic resistances and these portions 185 and 40 186 will therefore be termed resistance portions. Between the piston portions 183 and 184 the valve 178 is provided with collars 187 and 188 which are spaced from the wall of the bore through the valve bushing to provide hydraulic resistance 45 to the flow of the hydraulic fluid therethrough. Between the piston portions 183 and 184 and the collars 187 and 188 are provided cannelures 189, 190 and 191 which effect connection between the radial ports in the bushing in different combinations; and the purpose for the several hydraulic resistances will be explained in full later.

It is with the ports 170 that the conduit 161 terminates while the conduit 162 terminates in the ports 176 from which it will be seen that the pressure in the said ports is connected to the 55 opposite ends of the shuttle reversing valve 178. The ports 171 have connected therewith one end of a conduit 192 which terminates at its other end in the ports 84 of the starting and stopping valve 79. The ports 172 and 174 have 60 respectively connected therewith one termini of ports or conduits 193 and 194 which respectively terminate at their other ends in similar independently adjustable choke valves 195 and 196. Connected with the ports 173 is one end 65 of the conduit 166, which as above noted, connects with the conduit 167 emptying into the tank or sump 20. The ports 175 have connected therewith one end of a conduit 197 which terminates at its other end in the piston reversing 70 valve 124.

The piston reversing valve 124 is shown structurally in Figure 8 and comprises a valve bushing 198 pressed into a bore in the block 127 and 75 conveniently disposed adjacent the valve 125.

The valve bushing 198 has formed therethrough a plurality of sets of radial ports 199, 200, 201, 202, 203, 204 and 205, each set being encircled by a similar circumferential groove 206 formed in the exterior of the bushing 198. The bushing is closed at opposite ends by means of plugs 207 and 208 which limit the travel of a valve relative to the bore of the bushing. The said valve 209 is of the shuttling type and pressure actuated between the said stop plugs 207 and 208. The valve 209 is provided with piston portions 210, 211 and 212 adapted to connect in different combinations the several sets of radial ports by forming between them cannelures 213 and 214. It is with the ports 202 15 that the pressure conduit 123 from the pump connects, while the ports 201 and 203 on opposite sides of the ports 202 respectively connect with one end of conduits 215 and 216 which respectively terminate at ports in the 20 right and left hand ends of the piston cylinder 214, as seen in Figure 13. The ports 200 and 204 respectively connect through conduits or ports 217 and 218 with the adjustable valves 196 and 195 and therefore with the conduits 194 and 193 extending from said valves. The port 199 is at the other terminal of the conduit 197 from the valve 125, as above described, while the ports 205 connect with one end of a pipe or conduit 219 which terminates at its other 25 end in the port 83 of the valve 79.

The remaining port 85 of the valve 79 is connected by a pipe or conduit 220 with the main return conduit 167.

The adjustable throttle valves 195 and 196 35 are shown structurally in Figure 5, and since they are identical in construction it is deemed sufficient if but one of them be described in detail. Therefore, and as seen in Figure 5, the throttle valve 196 comprises a stem 221 40 having a knob 222 at one end thereof and a valve portion 223 at its other end. The valve portion 223 is adapted to co-operate with a valve seat 224 formed between the conduit or port 194. From this it will be seen that the 45 amount of flow between the ports 217 and 194 will depend upon the relative positioning or co-operation between the valve 223 and the seat 224.

The operation of this mechanism is as follows:

The grinding wheel spindle is first rotated through the V belts 95 to effect the rotation of the grinding wheel. It is also assumed, in the case of a centerless grinder, that the regulating wheel is likewise rotated at its proper speed. The infeed mechanism motor 66 is then started for operating the mechanism contained within or associated with the housing 36. This, of course, effects the rotation of the worm shaft 62 and worm 61 for rotating through the worm 60 the cam shaft 58 and the cams 52 and 67 thereon. The cam 52 substantially immediately shifts the work supporting carriages into position for effecting the engagement of the work 65 with the grinding wheel to effect a stock removal from the work.

Substantially at this point the cam 67, through the arm 73, shifts the valve 79 to the position shown in Figures 12 and 13, thereby 70 connecting the conduits 192 and 219 or completing the hydraulic circuit whereupon the spindle reciprocating mechanism is operated. The flow of pressure at this time will be through the conduits 123 and 160 to the valve 126 for 75

connecting through the ports 133 and 132 the pressure with the conduit 161. The pressure in this conduit is connected through the valve 125 and its ports 170 and 171 with the conduit 5 192 and therefore the conduit 219. This pressure then acts on the right hand end of the shuttling piston reversing valve 209 for shifting it to the position shown in Figure 13. When this valve reaches the position shown it connects the ports 202 and 203 so that the pressure in the conduit 123 then enters the conduit 216 10 and acts on the right hand end of the spindle reciprocating piston, thereby shifting the said piston, spindle and its grinding wheel to the left or across the work. The hydraulic medium 15 15 on the other side of the piston is at this time exhausted through the conduit 215, ports 201 and 200 of the valve 124 to the port or conduit 217 and the throttle valve 196. The valve 196 20 is adjusted to determine the rate of escape of the hydraulic medium and therefore to determine the rate of flow of the medium and consequently the rate of movement of the piston, spindle and grinding wheel. After the medium 25 passes the throttling valve 196 it flows through the conduit 194 to the pilot valve 125 whose ports 174 and 173 connect the medium with conduits 166 and 167 to the tank 120.

This movement of the spindle, grinding wheel and piston continues to the left until the nut 154, which is moving with the piston, engages the valve shifter arm 150 for oscillating the shaft 148 and valve shifter 147 to change the position of the valve 126. In other words, 30

35 through the mechanism above described the valve member 138 is shifted to a position for connecting through its cannelure 143 the ports 133 and 134 and therefore connecting the branch pressure conduit 160 with the conduit 162. At this time the pressure in the conduit 162 acts on the left hand end of the shuttling pilot valve member 178 for shifting same to the right and connect ports 176 and 175 to permit the flow of the medium into the conduit 40 45 197. The shifting of the pilot valve member 178 to the right will place the hydraulic resistance collar 187 thereon between the ports 174 and 173, thereby setting up a resistance to the flow of the hydraulic medium through 50 the conduit 194 from the exhaust side of the spindle reciprocating piston. It will be appreciated that the piston is near the end of its stroke when the valve mechanism 126 is actuated, but the piston is not quite to the end of 55 its stroke; therefore by throttling this exhaust near the end of its stroke a cushioning action is had which absolutely prevents a forcible bumping of the piston against a positive stop, in this case the positive stop being provided 60 by the nut 154 and cylinder head 116. It will, therefore, be seen that the spindle is reversed at one end of its stroke before it actually contacts with the positive stop.

Simultaneously with the action just described 65 the piston reversing valve mechanism 124 is being operated by the fluid passing through the conduit 197. This fluid acting on the left hand end of the piston member 209 shifts same toward the right, as seen in Figure 13, substantially 70 immediately shutting off the flow of the pressure through the pressure conduit 123 and the port 202, thereby stopping the actuating force for shifting the spindle and parts associated therewith. The movement of the valve member 209 effects 75 the discharge of the medium at the other end

thereof, previously utilized for shifting the valve to the position it now occupies. This exhausted medium is through the ports 205, conduit 219, ports 83 and 84 of the valve mechanism 79, and conduit 192 to the valve mechanism 125. 5 At this time the hydraulic resistance collar 185 is more or less overlying the ports 171 to more or less restrict the flow of fluid therethrough, depending upon the adjustment of the stop 179. This, as above described, sets up an 10 hydraulic resistance which slows up or tends to delay the actual shifting of the valve member 209, thereby causing a delay in the movement of the spindle and parts associated therewith at one end of their stroke. This delay 15 may be regulated or varied by varying the position of the stop 179, thereby changing the hydraulic resistance or throttling action on the flow of the fluid through the conduit 192 and port 171. It is to be understood that the 20 stop 179 may be adjusted to a position to maintain the ports 171 uncovered, thereby offering no resistance to the flow of fluid therethrough and permitting a rapid or substantially instantaneous shifting of the valve member 209. 25 From this it will be seen that the rate of shifting of the valve member 209 may be adjusted for effecting a variable delay at one end of the reversal of the spindle and parts associated therewith. 30

The valve 209 is finally shifted to engage its other stop 207, thereby connecting the ports 202 and 201 for directing the hydraulic medium in the conduit 123 against the left hand end of the spindle reciprocating piston for shifting the 35 parts to the right, as seen in Figure 13.

This movement of the spindle and parts associated therewith to the right continues until the flange 153 on the sleeve nut 155 engages the valve shifting lever 150, whereupon the 40 valve mechanism is actuated for shifting its valve member 138 to the position shown in Figures 8 and 13. At this time the pressure then acts through the conduit 161 on the right hand end of the shuttling pilot valve for shifting same to the position shown in the drawings. Depending upon the adjustment of adjustable stop 180 the hydraulic resistance collar 186 takes a position with respect to the ports 175 for controlling the flow therethrough. 45 50

With the pilot valve member 178 in its left hand position the hydraulic pressure is down through the conduits 192 and 219 to the right hand end of the piston reversing valve member 209 for shifting same to the left. The movement of the valve member 209 to the left exhausts the medium ahead of it through the conduit 197, ports 175 and conduit 162 where it is connected through the valve mechanism 126 with the discharging conduits 165, 166 and 167. The movement of the piston reversing valve member 209 is delayed and controlled, however, by the hydraulic resistance collar 186 in the same manner as the reverse movement thereof was controlled as above described. 60 65 From this it will be seen that a delay may be provided at each end of the spindle stroke and that said delay may be varied or adjusted by merely varying the adjusting stops 179 and 180.

When the valve reaches the position shown in Figure 13 the spindle and the parts associated therewith are actuated to the left, this movement being controlled by the throttle valve 195 as described above. By the present con- 70 75

struction and since, when the spindle reciprocator is stopped, only one line to the spindle reversing valve is broken, the spindle and grinding wheel will always stop at the same end of its stroke. This will be appreciated when it is remembered that upon shifting of the valve 19 by the cam 67 the conduit or pipe 219 is connected with the pipe or conduit 220 and the sump, while upon reversal of the valve mechanism 126, as by the spindle, no flow of pressure will be had to the valve mechanism 124.

From the foregoing it is believed now evident that there has been provided a spindle reciprocating mechanism in which the movement of the spindle, and therefore the grinding wheel, may be independently controlled and independently varied in each direction so that a rate of speed in each direction may be provided, depending upon the nature and type of the work. It will also be noted that there may be provided a variable delay at each end of the spindle stroke, which variable delay may be independently varied or adjusted depending upon the desires of the operator. It will further be noted that the spindle is prevented from forcibly engaging a positive stop at each end of its stroke, yet the said limits of the reciprocatory stroke may be very accurately determined and maintained.

In order to vary the length of stroke of the spindle without in any wise changing or varying the adjustment above or without interfering with the said adjustments it is only necessary to adjust the nut 154 on the sleeve nut 155 and to adjust the flange 153 of the sleeve nut 155 on the extension 156 of the piston 113.

What is claimed is,

1. In a spindle reciprocating mechanism of the class described the combination of a housing having bearings formed therein, a spindle mounted in said bearings for rotation and axial movement relative thereto, means for effecting said axial reciprocation of the spindle, means for varying the rate of said reciprocation, and means for effecting a dwell at each end of said reciprocation.

2. In a spindle reciprocating mechanism of the class described the combination of a housing having bearings formed therein, a spindle mounted in said bearings for rotation and axial movement relative thereto, means for effecting said axial reciprocation of the spindle, means for varying the rate of said reciprocation, means for effecting a dwell at each end of said reciprocation, and means for varying the duration of said dwell.

3. A spindle reciprocating mechanism of the class described including in combination with a housing having mounted therein a spindle for rotative and axial movement relative thereto, of a piston and cylinder mechanism secured to said spindle for reciprocating same, an hydraulic circuit for actuating the piston and consequently the spindle, and independently adjustable means at each end of the reciprocatory stroke for limiting the movement of the piston in each direction.

4. A spindle reciprocating mechanism of the class described including in combination with a housing having mounted therein a spindle for rotative and axial movement relative thereto, of a piston and cylinder mechanism secured to said spindle for reciprocating same, an hydraulic circuit for actuating the piston and con-

sequently the spindle, adjustable means for limiting the movement of the piston in each direction, a valve in said circuit for reversing the flow therethrough to reverse the operation of the spindle, and means between the valve and piston movement limiting means whereby the said valve is operated.

5. A spindle reciprocating mechanism of the class described including in combination with a housing having mounted therein a spindle for rotative and axial movement relative thereto, of a piston and cylinder mechanism secured to said spindle for reciprocating same, an hydraulic circuit for actuating the piston and consequently the spindle, adjustable means for limiting the movement of the piston in each direction, a valve in said circuit for reversing the flow therethrough to reverse the operation of the spindle, means between the valve and piston movement limiting means whereby the said valve is operated, and a valve in said circuit for initiating and stopping the flow through the circuit.

6. In a spindle reciprocating mechanism of the class described the combination with a spindle supported for axial sliding movement within its bearings, of a piston secured to the spindle, an hydraulic circuit for reversely axially actuating the piston and consequently the spindle, a starting and stopping valve in said circuit, a pressure actuated reversing valve for alternately directing the pressure to opposite ends of the piston, and independently adjustable means for controlling the flow of the fluid from each end of said piston for thereby adjustably varying the rate of movement of the piston in each direction.

7. In a spindle reciprocating mechanism of the class described the combination of a piston secured to the spindle, an hydraulic circuit for reversely axially actuating the piston and consequently the spindle, a starting and stopping valve in said circuit, a pressure actuated reversing valve for alternately directing the pressure to opposite ends of the piston, independently adjustable means for controlling the flow of the fluid from each end of said piston for thereby adjustably varying the rate of movement of the piston in each direction, and means for delaying the operation of the pressure actuated reversing valve to provide a tarry in the movement of the piston.

8. In a spindle reciprocating mechanism of the class described the combination of a piston secured to the spindle, an hydraulic circuit for reversely axially actuating the piston and consequently the spindle, a starting and stopping valve in said circuit, a pressure actuated reversing valve for alternately directing the pressure to opposite ends of the piston, independently adjustable means for controlling the flow of the fluid from each end of said piston for thereby adjustably varying the rate of movement of the piston in each direction, and adjustable means for delaying the operation of the piston reversing valve whereby a variable delay at each end of the piston stroke is provided.

9. In a spindle reciprocating mechanism of the class described the combination of a piston secured to the spindle, an hydraulic circuit for reversely axially actuating the piston and consequently the spindle, a starting and stopping valve in said circuit, a pressure actuated reversing valve for alternately directing the pressure to opposite ends of the piston, independently adjustable means for controlling the flow of

- the fluid from each end of said piston for thereby adjustably varying the rate of movement of the piston in each direction, adjustable means for delaying the operation of the piston reversing valve whereby a variable delay at each end of the piston stroke is provided, and means for slowing down the movement of the piston at each end of its stroke to eliminate a forcible engagement between the piston and its stop.
10. In a spindle reciprocating mechanism of the class described the combination of a piston secured to the spindle, an hydraulic circuit for reversely axially actuating the piston and consequently the spindle, a starting and stopping valve in said circuit, a pressure actuated reversing valve for alternately directing the pressure to opposite ends of the piston, independently adjustable means for controlling the flow of the fluid from each end of said piston for thereby adjustably varying the rate of movement of the piston in each direction, adjustable means for delaying the operation of the piston reversing valve whereby a variable delay at each end of the piston stroke is provided, said means comprising an adjustable hydraulic resistance which limits the exhaust from the pressure operated piston reversing valve, and means for varying the effectiveness of said resistances.
11. In a spindle reciprocating mechanism of the class described the combination with bearings, and a spindle mounted therein for reciprocation relative thereto, of an hydraulically actuated piston secured to said spindle, an hydraulic circuit for actuating the piston, a starting and stopping valve in the circuit for initiating and stopping the movement of the piston, a reversing valve for alternately connecting the pressure side of the circuit with the ends of the piston, independent and adjustable means for controlling the exhaust flow from the piston to vary the rate of travel of the piston in each direction, independently adjustable means for delaying the operation of the reversing valve whereby to effect an adjustable delay in the movement of the piston at each end of its stroke, and means operable just prior to each end of the piston stroke for cushioning same and slowing down its movement for thereby eliminating jars and the like incident to the reversal of the piston.
12. In a spindle reciprocating mechanism of the class described the combination with bearings, and a spindle mounted therein for reciprocation relative thereto, of an hydraulically actuated piston secured to said spindle, an hydraulic circuit for actuating the piston, a starting and stopping valve in the circuit for initiating and stopping the movement of the piston, a reversing valve for alternately connecting the pressure side of the circuit with the ends of the piston, independent and adjustable means for controlling the exhaust flow from the piston to vary the rate of travel of the piston in each direction, independently adjustable means for delaying the operation of the reversing valve whereby to effect an adjustable delay in the movement of the piston at each end of its stroke, means operable just prior to each end of the piston stroke for cushioning same and slowing down its movement for thereby eliminating jars and the like incident to the reversal of the piston, and adjustable means associated with the piston for positively limiting the movement of the piston in each direction.
13. A mechanism for effecting a limited reciprocation of a grinding wheel spindle or the like with respect to its bearings including a piston member directly associated with the spindle for positively effecting back and forth movements thereof, hydraulic mechanism for effecting said movements of the piston, a control valve, lost motion mechanical connections between the control valve and the piston for effecting intermittent actuations of the valve from movements of the piston, and an hydraulic actuating system including serially arranged valve mechanisms controlled by the mechanical connection with the first mentioned valve for determining the operative effect of the piston.
14. A mechanism for effecting a limited reciprocation of a grinding wheel spindle or the like with respect to its bearings including a piston member directly associated with the spindle for positively effecting back and forth movements thereof, hydraulic mechanism for effecting said movements of the piston, a control valve, lost motion mechanical connections between the control valve and the piston for effecting intermittent actuations of the valve from movements of the piston, an hydraulic actuating system including serially arranged valve mechanisms controlled by the mechanical connection with the first mentioned valve for determining the operative effect of the piston, and additional manually adjustable devices for varying the rate of movement of the piston and attached spindle in a valve determined direction.
15. A mechanism for effecting a limited reciprocation of a grinding wheel spindle or the like with respect to its bearings including a piston member directly associated with the spindle for positively effecting back and forth movements thereof, hydraulic mechanism for effecting said movements of the piston, a control valve, lost motion mechanical connections between the control valve and the piston for effecting intermittent actuations of the valve from movements of the piston, an hydraulic actuating system including serially arranged valve mechanisms controlled by the mechanical connection with the first mentioned valve for determining the operative effect of the piston, and additional manually adjustable means for varying the lost motion connection between the piston mechanism and the valve actuating member for varying the period between reversals effective through the hydraulic system.
16. A mechanism for effecting a limited reciprocation of a grinding wheel spindle or the like with respect to its bearings including a piston member directly associated with the spindle for positively effecting back and forth movements thereof, hydraulic mechanism for effecting said movements of the piston, a control valve, lost motion mechanical connections between the control valve and the piston for effecting intermittent actuations of the valve from movements of the piston, an hydraulic actuating system including serially arranged valve mechanisms controlled by the mechanical connection with the first mentioned valve for determining the operative effect of the piston, said hydraulic system including a power transmitting conduit, and additional valve means operable to interrupt the flow through said conduit.
17. A mechanism for effecting a limited reciprocation of a grinding wheel spindle or the like with respect to its bearings including a piston member directly associated with the spin-

idle for positively effecting back and forth movements thereof, hydraulic mechanism for effecting said movements of the piston, a control valve, lost motion mechanical connections between the control valve and the piston for effecting intermittent actuations of the valve from movements of the piston, an hydraulic actuating system including serially arranged valve mechanisms controlled by the mechanical con-

nection with the first mentioned valve for determining the operative effect of the piston, said hydraulic system including a power transmitting conduit, additional valve means operable to interrupt the flow through said conduit, and power means operative automatically to determine the several positionings of said last mentioned valve.
